RADIOACTIVE BATTERY

John H. Birden and Kenneth C. Jordan, Dayton, Ohio, assignors to the United States of America as represented by the United States Atomic Energy Commission

Application April 5, 1955, Serial No. 499,543

2 Claims. (Cl. 136—4)

The present invention relates to the generation of electrical energy from radioactivity, and more especially to a novel battery or cell wherein the energy of the charged particles emitted by a radioactive isotope is converted into heat energy and then is converted into electricity, in amounts for doing useful work, by means of a thermopile.

It has been heretofore proposed that very small electrical currents could be generated by collection of the beta particles emitted from a radioactive isotope on a charged surface, that small currents may be generated between two electrochemically dissimilar electrodes separated by an ionizable gas by forcibly ionizing the gas with radiation and connecting a load across the electrodes, and that electrons from radioactive strontium be utilized to bombard a semi-conductor having a large junction formed by an impurity therein. None of the proposed devices have proved entirely satisfactory for practical power packs, principally because they are voltage sources of relatively high internal impedances. Where large currents are required, the internal power loss due to the internal impedance is so great that the batteries must be made undesirably large in physical size to overcome their inefficient operation. Moreover, relatively small currents have been obtained from prior radioactive batteries, and they have been costly and difficult to construct. Great care must be taken to reduce the radiation hazard to the user or, associated equipment, and the amounts of radioactive material which can be used must accordingly be kept rather small.

With a knowledge of the difficulties associated with constructing radioactive batteries of the types known to the prior art, the inventors have for a primary object of their invention production of a novel radioactive voltage source of inherently low internal impedance, so that large amounts of useful power may be delivered by a source of reasonable physical size. A further object is to provide a radioactive battery which creates no radiation hazard of any kind to the user or to equipment. Yet another object is to provide a source that is relatively simple to construct with available structural materials. Other objects and advantages of the present invention will become apparent from the following detailed description of certain preferred embodiments thereof, when read in connection with the appended drawings, wherein:

Figure 1 illustrates one embodiment of our novel electric cell;

Figure 2 shows an alternative, preferred form of the active portion of our cell;

Figure 3 shows the outer envelope enclosing the portion shown in Figure 2;

Figure 4 illustrates schematically the electrical circuit of our novel cell; and

Figure 5 shows schematically the thermal circuit of our cell.

According to our invention, electrical energy is generated by converting the energy of radioactive decay to

2

heat energy and then converting the heat energy to electrical energy. A radioactive material of high specific activity is sealed inside a suitable container which contacts thermally the "hot" junctions of a thermopile—a plurality of series-connected, alternately hot and cold thermojunctions. The cold junctions of the thermopile are thermally insulated from the hot junctions and from the inner container and are electrically connected in series relationship with the hot junctions. Preferably, for development of maximum power, our cell is so designed that one-half the heat generated by radioactive decay of the source is transferred to the outer container by way of equal-resistance thermopile leads, and the internal series resistance of the thermopile is made equal to the load resistance to be connected thereto.

Referring now to Figure 1, in one form our cell may comprise a spherical capsule 1 containing an intensely radioactive material therein, a thermopile of dissimilar metal leads 2, 3 provided with hot junctions 4 and cold junctions 5, an outer container 6 enclosing the assembly, and thermal insulating material, not shown in the interest of clarity, interposed between capsule 1 and container 6. Each hot junction 4 is placed in thermal contact with capsule 1, while each cold junction 5 contacts container 6. The thermopile leads are brought out through tube socket or base 8, which fits tightly into the bottom of container 6. Suitable materials of construction for this cell are shown in Table II, column 1.

Referring now to Figures 2 and 3, a preferred cell construction comprises a small cylindrical metal capsule 21 containing a source of highly radioactive material; two groups 22, 23 of thermocouples, each couple having a hot junction in thermal contact with capsule 21 and a cold junction formed externally to one of the insulator plates 24, 25; an outer sleeve 31 surrounding the assembly for protection and insulation from the outside air; end caps 32, 33 closing the ends of the sleeve; and mechanical spacers 28 to separate the closely-spaced wires to prevent contact between wires. The thermal insulator, preferably a light powder filling the space between capsule and container, is not shown for clarity. The entire space between plates 24, 25 is normally filled with the insulator, which is not electrically conductive. External leads 26, 27 are provided from opposite terminals of the thermopile, the two groups 22, 23 of couples being electrically connected in series. Materials used in construction of the battery illustrated are shown in Table II, column 2. The thermocouple wires extend through parallel rows of holes in the base plates 24, 25, each plate being formed of two half-discs held together by straps near their periphery. The end caps may preferably be hermetically sealed to sleeve 31 and leads 26, 27 brought out through vacuum-tight seals 34, 35. Each cold junction may be cemented to the outer container by an electrically-insulating, thermally conductive cement to provide a large surface area for cooling of the cold junctions. The spacers 28 are not required if sufficient tension is put on the wires to keep them separate.

Referring now to Figure 4, the simple electrical circuit of the thermopile comprises a plurality of resistances, (r_1, r_2 represent the electrical resistance per lead of each type of thermocouple wire in ohms and r is the resistance per couple). The leads are connected in series forming "n" hot or cold junctions and the opposite ends being connected to a load represented by $n(r_1+r_2)$ ohms. We have found that maximum power will be developed from our radioactive battery when it is connected to a load resistance equal to the internal resistance of the battery. The power developed W_L will be given by the expression $(ne)^2/4nr$, where e is the voltage generated per couple. The efficiency of the radioactive battery may be found

from the expression [Eff=100 $W_L/W_S=25 ne^2/W_S r$] where W_S is the heat generated by the radioactivity within the capsule, and r is the series resistance of both leads forming a couple.

We have found that for maximum efficiency, the leads of our thermopile should have a thermoresistance equal to the sum of the thermoresistances of the space between the capsule and the outer container and the thermoresistance from the capsule to the hot junctions. We have further found that the diameter of each type of wire in the thermopile should be so chosen that the thermoresistance of each lead is the same, for maximum efficiency.

Referring now to Figure 5, the heat W_S generated by radioactivity within the capsule, travels from the capsule across the thermoresistance R_C from the capsule to the hot junctions, which are at temperature T_1 . From the hot junctions the heat travels along all the wires between hot and cold junctions, the thermoresistance of all the wires being represented by R_t , to the cold junctions, which are at temperature T_2 . Some of the heat from the capsule also flows through the space between the capsule and the outer container, the thermoresistance of that space being represented by R_S . All of the heat from the source except that converted to electrical power flows through the network shown in Figure 5.

The electrical resistivity p_e and thermal resistivity p_t of the wires in the thermopile are related by the Wiedemann-Franz constant

$$a = \frac{p_e T}{p_t}$$

If the diameter of each wire is chosen so that the thermal resistance r_t of each lead is the same, the thermal resistance R_t of the n thermally parallel leads is given by

$$r_t$$

$$2n$$

For maximum efficiency, R_t should equal the sum of $R_S + R_C$. It may be seen that the maximum efficiency depends upon and varies inversely with Wiedemann-Franz constants of the thermopile wires selected. Therefore, the couple providing the greatest thermopower is not necessarily the best choice for the radioactive battery. If $R_t = R_S + R_C$, then it can be shown that the maximum efficiency $E = 3B^2(T_1 - T_2)/(a_1 + a_2)(1 + m)(T_1 + T_2)$, where B is the thermoelectric power of each thermocouple in volts/ $^{\circ}$ C. and m is the ratio of R_C to R_S . T_1 and T_2 are in degrees kelvin.

The efficiency of the battery does not depend upon the number of junctions; that is, increasing the number of junctions does not provide more efficient utilization of the heat. Moreover, the thermoresistance between the capsule and the hot junctions will increase slightly with the number of junctions, thus actually decreasing the efficiency. The internal resistance of the battery will increase as the square of the number of junctions, while the total voltage developed will be proportional to the number of junctions employed.

In designing the radioactive battery for meeting specified requirements, the type of thermocouple to be used should be selected first. Since efficiency is proportional to the square of the thermoelectric power, selection of materials will be a most important factor. However, as above stated, the Wiedemann-Franz constant and the resistivity of the thermocouple wires must be considered, as should be the melting points and the welding or soldering properties of the wires. Chromel-constantan and iron-constantan have high thermoelectric power and are entirely satisfactory in other respects. With a fixed number of junctions, and for maximum efficiency, the radius of the wire to be used depends upon the Wiedemann-Franz constant and the resistivity, so that a Chromel wire, because of its much higher resistivity must be substantially larger than the iron wire. Although the large wire reduces the thermocouple efficiency somewhat, for

most purposes the battery efficiency with a Chromel junction will be higher than with an iron junction.

The heat source should be next considered, important factors being the availability of highly active materials, the specific activity of the isotope used, the relative ease of handling, including the dangerous radiations given off, and the half life of the radioactive material. Any radioactive isotope could be used, but strontium-90 and polonium-210 appear to be most suitable from a cost per curie standpoint, and require a minimum of radiation shielding. Polonium-208 is ideally suited for battery use except for its excessive cost. In construction of the source, polonium may be volatilized into a capsule or container which is then closed with a plug and coated with nickel. Polonium has a high specific activity and gives off 5.4 mev. energy per disintegration. This permits the use of heat sources whose size and heat loss is determined only by mechanical considerations, and results in a minimum number of curies of activity required for a given quantity of heat produced. Strontium-90 is available in sealed containers and is better suited for a long-lived battery in that the useful life would be from 60 to 70 times the life of the Po battery.

If a battery is to be designed to deliver a maximum power W_L into a load R_L , with a load current I_L and a developed voltage of V_L , the equations for optimum battery design based on our battery having an efficiency of 0.2 percent, are:

$$R_L = \frac{V_L^2}{W_L \times 10^{-3}} \text{ ohms}$$

$$I_L = \frac{W_L}{V_L} \text{ milliamperes}$$

$$Po = \frac{Sr}{5} = \frac{31.24 W_L}{2} \text{ curies}$$

$$N = \frac{V_L}{9.4 \times 10^{-3}}$$

when N is the number of junctions required, Po is the curies of polonium required, and Sr is the curies of strontium required.

Table I lists two examples of our novel batteries calculated from these equations, based upon an efficiency of 0.2 percent attained by a battery constructed and tested.

TABLE I

Number of Junctions	5	50
Open-circuit voltage (millivolts)	94	940
Load voltage (millivolts)	47	470
Load (ohms)	1.1	18.4
Power delivered (milliwatts)	2	12
Load current (milliamperes)	42	12.8
Curies Polonium	32	187
Curies Strontium	100	935

It is apparent that we have for the first time provided suitable and practical batteries for electric generation capable of furnishing sufficient amounts of electrical power to be commercially useful, yet which are smaller, lighter, and can do more work than some dry cells. We have demonstrated that with relatively small physical dimensions we can provide an electric cell having extremely long life, even while delivering full rated current, and which can produce sufficient amounts of current to operate, for example, a transistorized radio circuit such as that shown in "Radio and Television News," February 1953, page 37. Moreover, the output of our cells is not affected by temperature of its environment so adversely as are dry cells.

It will be apparent to those skilled in the art that the source of radioactivity might be incorporated into the hot junction itself, rather than placed in a container and thermally connected to the junction. It will be further apparent that isotopes which emit only alpha particles are to be preferred, since the problem of shielding the dangerous radiations therefrom is easily met, whereas sources which emit hard gamma and beta rays produce dangerous

radiation hazards. For maximum efficiency, the source material shown should provide sufficient energy per unit volume, and should give maximum energy per disintegration. Mechanical requirements presently set a minimum size for the source capsule. The volume of such capsule is larger than the volume of polonium-210 required, but substantially that required for strontium-90.

Since the hot junctions must not make electrical contact with each other, but must all be thermally connected to the source, heavy insulating cement such as "Sauereisen" should be used for the hot and cold junctions. The cement should provide at least fair heat conduction, good

2. A radioactive cell comprising a source of polonium-210 sealed in a thermally-conductive capsule; a plurality of series-connected thermocouples having output terminals and provided with alternate junctions contacting said capsule in good thermal contact but electrically insulated therefrom; a pair of thermal and electrical insulator support members on opposite sides of said capsule for receiving the thermocouple wires and insulating the remaining junctions from said source; spacers for maintaining said supports in fixed relation; an evacuated outer envelope; evacuation of said envelope providing effective thermal insulation between said thermocouple junctions.

electrical insulation, must be temperature-stable at very high temperatures, and must provide good adhesion for structural purposes.

If hermetically sealed, and evacuated cells are not provided, a good thermal insulator such as "Santocel," a 45 silica aerogel should be provided in the space between the source and the outer container.

Having thus described our invention, we claim:

1. A radioactive cell comprising an evacuated outer envelope, a thermally-conducting capsule containing radioactive material characterized by emission of radiation selected from the group consisting of alpha particles and beta rays disposed therewithin, and a thermopile having two groups of alternate junctions and provided with a pair of output terminals forming the cell output, one group of junctions being in direct thermal contact with said capsule and electrically insulated therefrom and the other group being in thermal contact with said envelope whereby a temperature difference is maintained across said thermopile.
